UNITED STATES PATENT OFFICE.

JOHN A. SZYMANSKI AND VINCENT A. SZYMANSKI, OF DETROIT, MICHIGAN; SAID JOHN A. SZYMANSKI ASSIGNOR TO SAID VINCENT A. SZYMANSKI.

PAPER-VENDING MACHINE.

1,405,462.

Specification of Letters Patent.

Patented Feb. 7, 1922.

Application filed December 29, 1919. Serial No. 348,202.

To all whom it may concern:

Be it known that we, JOHN A. SZYMANSKI and VINCENT A. SZYMANSKI, citizens of the Republic of Poland, residing at Detroit, in the county of Wayne and State of Michigan, have invented certain new and useful Improvements in Paper-Vending Machines, of which the following is a specification.

This invention relates to paper vending machines and has for its object a coin-controlled paper vending machine which can be utilized to sell newspapers. The machine is provided with special coin apparatus which requires the use of at least two cents to allow the operating parts to be put into operation. It is also provided with an arrangement whereby the machine may be utilized for papers of varying thicknesses. These and other objects will more fully appear in the specification following.

In the drawings,—

Fig. 1 is a side elevation of the operating parts of the machine, the casing being shown in vertical section.

Fig. 2 is a front elevation of the operating parts at one side, the casing being shown in vertical section.

Fig. 3 is a detailed view showing the coin-controlled clutch.

Fig. 4 is a section on the line 4—4 showing this clutch and adjacent parts.

Fig. 5 is a similar section showing the clutch plunger released.

Fig. 6 is a detailed view of the coin-controlling apparatus in connection with the coin slide. The position of this apparatus with respect to the rest of the machine is shown in Fig. 2.

Fig. 7 is a section on the line 7—7 of Fig. 6.

Fig. 8 is a view from the left of the cam or clutch-plunger control α shown in Fig. 6.

Fig. 9 is a horizontal section through the paper bin showing especially the arrangement of operating levers and slides.

Fig. 10 is a vertical section through the lower portion of the paper bin and through the discharge chute showing the slides in the position they occupy just before the machine is operated.

Fig. 11 is a similar view showing the slides in the position they occupy just after the paper is discharged.

Fig. 12 is a section on the line 12—12 of Fig. 10.

The crankshaft 3 has a peculiar formation shown at best in Fig. 9. Two oppositely-directed throws, 180 degrees apart, are at both sides of the bin g . By passing through the side wall of the bin the crankshaft is suitably journaled. To the forward throws of the crankshaft shown in Fig. 9 are attached the connecting rods 5. To the rear throws shown in this figure are connected the connecting rods 6. The connecting rods 5 are attached to the upper slide 7 (see Fig. 11). This slide is simply a flat strip of metal which slides in the slot 8 formed in a metal angle strip 9. The angle character of this strip appears in Figs. 9 and 2. Similarly the lower slide 10 has the edges of the sheet that forms the top of the slide protruding into the slot 11 (Fig. 10). This slot 11 is in an angle strip 12 secured to the bottom of the angle strip 9 (see Fig. 1).

Looking at Fig. 9 it will be seen that the end of the connecting rod 6 is connected with a bar 13. Now examining Figs. 10 and 11, one will see the bar 13 is riveted to the slide 10. Hence these two slides are connected to the connecting rods that operate in connection with the two oppositely-directed pairs of throws of the crankshaft. In Fig. 10 the position of the slides before the crank is turned is shown. The papers are supported on the bottom of the bin and are prevented from falling through the orifice 14 at the bottom of the bin by the slide 10. Supposing the crank is turned, two cents having been placed in the slot f , and the slide d having been depressed to lift the clutch-plunger control α and allow the clutch-plunger v to swing out, this allows the crank to pick up the crankshaft 3. The rotation of the crank is clockwise. This causes the slide 7 shown in Fig. 9 to advance into the bin and the slide 10 to withdraw out of the bin. Comparing Figs. 10 and 11, it will be found that supposing a pile of papers to be shown in Fig. 10, the lowermost paper would rest on the top of the lower slide 10. The advancing in of the upper slide 7 allows the pointed inner edge or nose of this slide (see at 15, Fig. 9) to ram in between the last paper on the pile and its next above neighbor. Thereby the upper slide temporarily supports the pile while the lower slide 10 withdraws and allows the lowermost paper to drop through

105
110

the orifice 14, as does the newspaper shown in the dotted lines of Fig. 11. Immediately the paper is dropped through this orifice it slides down the spout 16 into the hands 5 of the operator. Note that the cross-travelling of these two slides and the upper slide supports the pile of papers behind the one to be dropped while the dropping takes place, and secondly when the parts rear- 10 range themselves in returning to their initial position, the lower slide goes in under the pile as the upper slide withdraws.

In order to insure the complete operation of the slides and the return of the clutch 15 parts to their starting position, the counter-weights with cords 17 running over the sheaves 18, 19, 20 and 21 are connected as at 22 and 23 (Fig. 2) with the throws of the crankshaft. This insures the parts comple- 20 ting a cycle of operation although the operator may stop the turning of the crank when his paper has dropped through. Shock absorbing springs 25 are utilized in the cords to take up any undue shocks. The 25 spring 26 (Fig. 2) is utilized to return the slide *d* to its initial position.

It might be wondered how this machine is adapted for newspapers when they are of varying thicknesses. This is nicely taken 30 care of by having a presser foot or roll 27 on the end of a presser rod 28 (Figs. 10 and 2). An examination of Fig. 2 will show that this rod is acted upon by the eccentric 29 on the end of the shaft 30 (see Fig. 10) that 35 runs through the top of the bin and is pro- vided with a knurled head 31 by which it may be turned. This knurled head 31 has a spring finger 32 adapted to run over a seg- ment of teeth 33 (see Fig. 12). Conse- 40 quently by turning this head 31 the presser roll 27 may be raised or lowered to press the upper slide more or less towards the lower slide, it being obvious that there will be a certain amount of yield to this upper slide 45 by reason of the sheet metal character of its construction. Of course, the spacing of the guide slots 8 and 11 determines the maximum spacing of the slides in the absence of bowing of the slides at the center.

50 The coins after they have been used are dropped into the run-way 34 (Figs. 7 and 1) where they may slide down into any convenient box 53, etc. The first cent is dropped down when the slide *d* is pushed down, the 55 cam-actuating lever *n* being raised high enough to drop the first cent, but after this is discharged, it drops back slightly and hence the second cent will not quite clear it.

This second cent is discharged by the plun- 60 ger *v* riding against the tail 36 (Figs. 1 and 8), of the clutch-plunger control *x*. This causes the control *x* to lift, thereby tipping the cam-actuating lever *n* and allowing the second coin to be discharged.

65 The plunger *v* is returned to its initial

position near the final portion of the rotation of the disks by striking against the inclined cam surface 37 (Fig. 8).

What we claim is:

1. In a machine of the character described, 70 the combination of a bin for storing papers provided with an inclined bottom having at the bottom a discharge orifice, the said bin and inclined bottom arranged to support the papers so that they lie upon such inclined 75 bottom parallel therewith, and means for discharging newspapers one at a time, comprising a pair of slides adapted to be slid in opposite directions past each other at the orifice.

2. In a machine of the character described, the combination of a bin provided with an inclined bottom having an orifice at one side and arranged to support the papers parallel with the bottom, and means for discharging 85 newspapers one at a time, comprising an upper and lower slide spaced the width of a newspaper and adapted to be reciprocated in opposite directions past each other at the said orifice in planes parallel with said inclined bottom.

3. In a machine of the character described, the combination of a bin provided with an inclined bottom having a discharge orifice at the bottom of the inclination, and means for 95 discharging papers one at a time, comprising a pair of oppositely-reciprocated and spaced slides adapted to pass each other at the orifice, the upper slide having a nose to engage between the lowermost paper and the 100 rest of the pile.

4. In a machine of the character described, the combination of a bin provided with an inclined bottom having a discharge orifice at the bottom of the inclination, a pair of 105 spaced and oppositely-reciprocated slides guarding said discharge orifice, the upper slide serving to engage between the lowermost paper and the rest of the pile, and means for adjusting the spacing of the slides 110 to accommodate papers of varying thicknesses.

5. In a machine of the character de- 115 scribed, the combination of a bin provided with a discharge opening at its lowermost portion, means for discharging newspapers one at a time, comprising a pair of spaced slides, the upper one of which engages be- 120 tween the lowermost paper and the rest of the pile, and means for adjusting the spacing of the slides, comprising a presser foot provided with means for adjusting its pressure against the upper slide.

6. In a machine of the character de- 125 scribed, the combination of a bin provided with a discharge orifice, means for discharging newspapers one at a time, comprising a pair of opposite-travelling and spaced slides, and means for adjusting the spacing 130 of the two slides, comprising a presser roll,

- a presser roll rod, an eccentric for actuating the same, a shaft on which said eccentric is mounted, and devices for adjustably fixing the shaft in any position of rotation.
- 5 7. In a machine of the character described, the combination of a newspaper bin provided with a discharge orifice and a pair of oppositely and parallel travelling slides adapted to guard said orifice and select the 10 undermost paper on the slide, an actuating crank, and a clutch between the actuating member and the slides adapted to connect up the actuating member and the slides.
- 15 8. In a machine of the character described, a newspaper bin provided with a discharge orifice, a pair of slides operating by opposite parallel travel to guard the discharge orifice, an actuator, and a clutch between the actuator and the slides.
- 20 9. In a machine of the character described, the combination of a bin for storing papers provided with an inclined bottom and discharge orifice, a pair of oppositely traveling slides supported to slide below the 25 discharge orifice, a crank having a pair of oppositely-directed throws, connections between each throw and one of the slides, an actuating handle, and a clutch between the actuating handle and the crankshaft.
- 30 10. In a machine of the character described, a bin adapted to store a pile of newspapers and provided with an arrangement so that newspapers are discharged through a discharge orifice in the bottom of the bin 35 at appointed times, and a pair of oppositely traveling slides located below said bin and spaced to take the thickness of a newspaper within given limits, a crankshaft for actuating said slides through suitable connec-
- tions, a pair of weights connecting with the 40 said slides for causing the slides to complete their travel when actuation is started, an actuating handle, and a clutch between the actuating handle and the crankshaft.
11. In a machine of the character described, a bin arranged to store papers and discharge the same through an orifice in the bottom of the bin, a pair of oppositely travelling slides below said orifice, a crankshaft having suitable connections for reciprocating the slides back and forth, a clutch, an actuating handle adapted to be connected up at appointed times with the crankshaft by the clutch, and a pair of weights connected up to the slides by connections including 50 springs for causing the slides to complete their movement even if the handle is not turned a complete turn.
12. In a machine of the character described, the combination of a bin for storing 55 papers provided with an inclined bottom having a discharge orifice at the bottom of the inclination, the said inclined bottom arranged to hold the papers in parallel relation therewith and the said discharge orifice being of sufficient size to permit the paper to overcome the friction with the inclined bottom and slide out the discharge orifice when the same is opened, and a pair 60 of slides for guarding said discharge orifice and permitting the lowermost paper to slide out while restraining the next uppermost paper.
- 65 In testimony whereof we affix our signatures.
- 70 JOHN A. SZYMANSKI.
VINCENT A. SZYMANSKI.
